Switch for burglar alarms, including a housing, a switch arm, a shackle, a support, a housing closure, a signal device, and a switch arm closure, all being of a novel construction.

UNITED STATES PATENT OFFICE

2,521,858

SWITCH FOR BURGLAR ALARMS

Russell H. Levy, Chicago, Ill.

Application April 10, 1946, Serial No. 660,910

7 Claims. (Cl. 200—54)

1

My invention relates to burglar alarms for association with slidable window sash, e. g., double-hung window sash.

An object of my invention is to provide a simple, dependable and easy-to-service alarm unit which economically may be manufactured and readily satisfactorily installed.

Another object of my invention is to improve the dependability and facilitate the serviceability maintenance of the alarm energizing switches of burglar alarms suitable for use in conjunction with slidable window sash.

Salient features of my invention are alarm energizing switches comprising actuating arms provided with novel friction tips. Each of these novel friction tips readily may be serviced to present a multiplicity of small arcuately convex contact areas to a smooth surface, such as a glass pane, between which and an alarm unit relative movement occurs as an incident to the opening of a window.

Other objects, features and advantages of my invention will appear from the following detailed description wherein reference is made to the accompanying three sheets of drawings in which:

Fig. 1 is a top view, partly in plan and partly in elevation, of a first embodiment of my invention;

Fig. 2 is a side view, partly in elevation and partly in section, of the same;

Fig. 3 is an end elevational view of the same;

Fig. 4 is a circuit diagram apropos of the equipment depicted in Figs. 1 to 3;

Fig. 5 is a side elevational view of a second embodiment of my invention;

Fig. 6 is a top plan view thereof;

Fig. 7 is an end elevational view thereof;

Fig. 8 is a side view, partly in elevation and partly in section, of a third embodiment of my invention; and

Fig. 9 is an end elevational view thereof.

Similar characters of reference refer to similar parts throughout the several views.

In the drawings, wherein the several embodiments of my invention are depicted as applied to double-hung window sash, A indicates the upper rail of a lower sash having a pane B, and C indicates the lower rail of an upper sash having a pane D.

In the first embodiment of my invention which is depicted in Figs. 1 to 4 inclusive, 10 indicates a metal housing provided with attaching ears 11—11 whereby it is adjustably secured on sash rail A with screws 12—12 extending through elongated slots 13—13. Housing 10 desirably is provided with a removable end closure 14.

Carried by and with housing 10, e. g., by being mounted on its top, is a signaling device, preferably an audible signaling device, which suitably may be an electric bell 15. It may be assumed

that housing 10 contains appropriate means (not shown) such as a dry cell battery or transformer from which is supplied electrical energy for actuating the signal 15. Usually I prefer to employ a dry cell battery. Carried by and within housing 10 is an adjustable support 16 for a switch arm 17.

Support 16 is preferably formed of a dielectric material, such as wood or a molded plastic, and may be in the form of an elongated bar having trunnions 18 and 19 which, respectively, have bearings in the fixed and removable end walls of housing 10. Trunnion 19 may have fixed thereto an external adjusting button 20. Support 16 is frictionally retained at any position to which it may be adjusted around the common axis of its trunnions 18 and 19.

Carried by support 16 is a shackle for the switch arm 17. Such shackle may consist of a U-shaped metal element 21, secured to support 16 by screw 21a, which has a metal pin 22 extending between its spaced-apart arms. Pin 22 extends freely through an over-size opening in the switch arm 17, and such switch arm 17 roughly is centered between the arms of the U-shaped element 21 by a pair of washers 23—23. An insulated flexible conductor 24 connects with switch arm 17, conveniently by being soldered or otherwise electrically joined with U-shaped metal element 21.

With respect to its shackle which I have just described, switch arm 17 is capable of a certain amount of universal movement. From such shackle switch arm 17 extends through an opening 25 in that end wall of housing 10 which is adjacent to sash pane D. Opening 25 is preferably but not necessarily circular. Riveted or otherwise attached to the outer end of switch arm 17 is a U-shaped disc-carrier 26.

Between the spaced-apart arms of disc-carrier 26 extends a pin 27 whereon is disposed a plurality of coaxial similar discs 28—28. Discs 28—28 are formed of relatively soft rubber or like yielding material, and each such disc preferably possesses a narrow continuous peripheral surface which is spaced from the corresponding surface of each contiguous disc. The relation of the discs 28—28 to each other, and to carrier 26 and pin 27, is such that the discs are frictionally held against turning on their common axis except when being serviced as hereinafter explained.

Formed in the removable end closure 14 of the housing 10, and desirably located above button 20, is a sight aperture 29. Carried by end closure 14 may be a master switch 30.

In Fig. 4 is a diagrammatically illustrated one of several equivalent circuit arrangements satisfactory for my purpose. In the specific arrangement shown, the audible alarm 15 has one side thereof grounded to housing 10 and its other side

connected with one of the poles of a dry cell battery. The other pole of the battery connects, through master switch 30, with switch arm 17.

Assuming master switch 30 to be open, the hereinbefore described burglar alarm is "set" by so adjusting the switch arm 17 that it lies out of electrical contact with the margin or margins of opening 25 while the several relatively narrow spaced-apart peripheries of the yielding discs 28-28 are presented to and bear against the inner surface of pane D. Such adjustment of arm 17 readily may be effected by manipulating button 20 while peering through aperture 29 to observe the relationship between arm 17 and the margin or margins of opening 25. Master switch 30 is now closed.

Thereafter, so long as the master switch 30 remains closed, any substantial relative movement between the two sash, or any substantial relative movement between the pane D and the housing 10, even though such last-mentioned relative movement does not result from movement between the two sash, will result in the switch arm contacting the edge of the hole 25 and thereby completing the circuit of the audible signaling device 15. The sensitivity of the equipment, in its response to relative movements between the pane D and the housing 10, whether those relative movements be vertical, horizontal, or between the vertical and the horizontal, depends upon the relative sizes of the switch arm 17 and the opening 25. By giving the opening 25 a diameter only slightly greater than the diameter of the switch arm 17, the alarm can be made so sensitive that it will respond to moderate window rattling caused by wind storms. Some people desire an alarm which is that sensitive. By making the diameter of opening 25 substantially greater than the diameter of switch arm 17, the equipment may be rendered less sensitive. When it is desired to effect relative movement between the two sash without sounding an alarm, the master switch 30 is thrown to its open position.

That second embodiment of my invention which is exhibited in Figs. 5 to 7 both inclusive comprises a suitable housing 40 provided with mounting ears 41 suitably slotted at 41a so that the housing adjustably may be mounted atop the rail A of the lower sash by screws 42-42. The housing 40 carries an audible signaling device 43 which is actuated by electrical energy supplied by a dry cell battery or electrical transformer (not shown) contained by the housing 40. It may be assumed that the audible signaling device 43 is included in a simple signal circuit which is closed to actuate the alarm whenever electrical connection is established between the two blade-receiving switch contact studs 44-44 which project outwardly from that end wall of housing 40 which faces the pane D.

At 45-45 is depicted a plurality of coaxial discs carried at the free end of a switch arm comprising a pair of blades 46-46 pivoted to a pair of blade mounting studs 47-47 which lie above the blade-receiving switch contact studs 44-44 which I have previously mentioned. The discs 45-45 which in this instance are provided by placing two similar soft rubber grommets upon a metal pin 48 connecting the switch blades 46-46, present very narrow — substantially edge-like — spaced-apart peripheral surfaces. The relationship of the soft rubber grommets to the switch blades 46 and the pin 48 is such that the grommets turn on the pin 48 only when they are serviced as herein-after explained.

Located above the studs 47-47 whereto the switch blades 46-46 are pivoted, is a pair of switch blade-receiving studs 49-49. These switch blade-receiving studs 49-49 are dummies in the sense that their engagement with the blades 46-46 of the switch arm does not result in energization of the alarm circuit.

In the embodiment of my invention just described, the switch arm is moved upwardly so that its blades engage in the studs 49-49 when the burglar alarm temporarily is to be rendered inoperative.

When the alarm is to be set, the switch arm is moved to a substantially horizontal position in which the peripheries of the several discs or grommet portions 45 bear against the adjacent surface of the pane D.

Thereafter any substantial opening movement of either sash with respect to the other will result in the engagement of the studs 44-44 by the blades 46-46 of the switch arm, and consequent sounding of the audible alarm.

Frequently the burglar alarm will be "set," as hereinbefore explained, with one or both of the sash in partially opened position. A salient advantage of the burglar alarm now under consideration is that its warning signal cannot be avoided by first moving a partially open sash to fully closed position and then opening one of the sash. In such an instance, the moving to its closed position of the partially open sash may somewhat elevate the several discs 45-45, but it leaves them bearing against the inner surface of pane D, ready to move the blades 46-46 of the switch arm to alarm circuit closing contact with studs 44-44 upon any subsequent opening movement of either sash. It is desirable that the disc-carrying end of the switch arm comprising the blades 46-46 be sufficiently heavy that such end of the switch arm moves downwardly whenever it is not restrained against such movement. Normally the weight of the switch blades 46-46, the pin 48 and the discs 45-45 will be sufficient to ensure this action of the switch arm. However, if in any instance such should not be the case, the switch arm should be additionally weighted at its free or disc-carrying end.

The third embodiment of my invention which is exhibited in Figs. 8 and 9 comprises a housing 50 provided with appropriately slotted mounting ears 51 wherewith it may be secured to the sash rail A with screws 52-52.

Carried with the housing 50, e. g., upon the top thereof, is an audible signal device which may be in the form of an electric bell 53. The housing 50 contains a dry cell battery or transformer (not shown) from which is supplied electrical energy to energize an alarm circuit controlled by the normally separated spring contact members 54 and 55.

The free end of spring contact 55 is conventionally shaped for cooperation with a contact operating roller 56. Roller 56 is pivoted at 57 to the inner end of a contact operating lever 58 which has its fulcrum at 59 and has its operating arm 60 projecting outwardly from the housing through a slot 61.

Secured upon the free end of the arm 60 is a U-shaped disc carrier 62 between the spaced-apart arms of which extends a pin 63 whereon a plurality of discs 64, of soft rubber or like yielding material, are coaxially mounted; these discs 64, like the corresponding elements of the previously described burglar alarms, being of equal diameters and presenting narrow spaced-apart

continuous circumferential surfaces. Here again the discs are provided by mounting a pair of conventional rubber grommets upon the pin 63, and the relationship of the grommets to the parts by which they are carried is such that the grommets do not turn upon the pin 63 except when they are being serviced as hereinafter explained.

It will be noted that the housing 50 contains an auxiliary spring blade 65 which is appropriately shaped for cooperation with the roller 56 of the switch lever. This spring blade 65 is a dummy in the sense that its movement in no way affects the signal circuit.

When the alarm of Figs. 8 and 9 temporarily is to be rendered inoperative, the operating arm 60 of the switch lever is moved to the upper one of its dotted positions of Fig. 8 and is retained by reason of the cooperation of switch lever roller 56 with the adjacent end of spring blade 65. In these circumstances, the contacts 54 and 55 are separated to render the signal circuit inoperative.

The burglar alarm just described is "set" by moving the operating arm 60 of the switch lever to its full line position of Fig. 8. With the arm 60 in such position, the signal circuit contacts 54 and 55 remain open. However, any subsequent substantial opening movement of either sash with respect to the other results in engagement of spring contact 55 by roller 56 and the cooperation of contacts 54 and 55 to energize the alarm circuit.

A feature which characterizes each of the hereinbefore described burglar alarms of my invention is a switch arm presenting to a smooth surface, such as a sash pane, a tip comprising a plurality of yielding relatively narrow spaced-apart concentric arcuately convex surfaces of equal radii. A switch arm equipped with such a tip may be relied upon to assume its signal energizing position in response to any substantial window opening relative movement between the window part by which the switch is carried and the smooth surface against which its tip bears. Even though the pressure of such a tip against a pane or other smooth surface is quite small, the yielding relatively narrow arcuately convex surfaces of the tip severally assume minute flats which cling to the contacted smooth surface with dependable tenacity for long periods of time. However, the minute flats of the tips eventually become more or less fixed and less tenacious. To guard against this, it is advisable occasionally to service my burglar alarms by rotating the discs of the switch arm tips thereof to vary the peripheral portions of the discs which bear against the pane or other smooth surface. The friction with which the discs of each tip normally are held against rotation relative to their associated switch arm need not and should not be so great as to render this servicing other than easy of accomplishment.

The smooth surface against which the switch arm tip bears may be a frame-carried surface rather than a sash-carried surface.

Each of the pins 21, 48 and 63 may be formed in one piece, or it may consist of two telescoping separable parts threaded one into the other.

Having thus illustrated and described three practical embodiments of my invention, what I claim as new and desire to secure by Letters Patent of the United States is:

1. A burglar alarm comprising a unit supportable by the upper rail of the lower one of a pair of double hung window sash, said unit compris-

ing a housing, an opening in the housing wall which is to face the pane of the upper sash, metal bounding said opening, an arm projecting from said housing through said opening, a relatively soft deformable tip, carried by said arm and engageable with the pane of the upper sash, by virtue of which said arm is caused to engage said boundary metal and make electrical contact therewith as the consequence of relative movement between the sash and the aforesaid pane, an adjustable support for said arm located within said housing, and a universal connection between said support and said arm.

2. A burglar alarm as specified in claim 1 wherein the wall of the housing lying opposite the housing wall in which is formed the opening through which the arm extends presents means for adjusting said support and a peep-hole through which may be observed the relationship of said arm to the metal bounding the opening through which the arm extends.

3. A burglar alarm comprising a unit supportable by a sliding window sash, said unit comprising a housing, an opening in a housing wall which is to face a surface with respect to which the sash is relatively movable to open position, metal bounding said opening, an arm projecting from said housing through said opening, a relatively soft deformable tip, carried by said arm and engaging with the aforesaid surface, by virtue of which said arm is caused to engage said boundary metal and make electrical contact therewith as the consequence of relative movement between the sash and the aforesaid surface, and an adjustable support for said arm located within said housing, and a universal connection between said support and said arm.

4. A burglar alarm comprising a unit supportable by a sliding window sash, mechanism comprised by said unit and adapted when actuated to cause the functioning of an alarm, a pivoted actuating arm forming a part of said mechanism, said arm having a set position from which it is movable to a position where it actuates said mechanism, and a tip member, rotatably frictionally carried by said arm and engageable with a plane surface with respect to which the sash is movable, by virtue of which said arm is held in said set position by said surface and is positively moved to the position where it actuates said mechanism as the consequence of opening movement of the sash, said tip member having a plurality of coaxial axially spaced-apart arcuately convex ridges that are formed of comparatively soft and somewhat deformable material and which simultaneously and substantially tangentially contact the aforementioned plane surface when the arm is being held in set position and while it is being positively moved to alarm-actuating position as aforesaid.

5. A burglar alarm comprising a unit supportable by a sliding window sash, mechanism comprised by said unit and adapted when actuated to cause the functioning of an alarm, a pivoted actuating arm forming a part of said mechanism, said arm having a set position from which it is movable to a position where it actuates said mechanism, and a tip member, carried by said arm and when the arm is in said set position being engageable with a plane surface with respect to which the sash is movable, by virtue of which said arm is positively moved to the position where it actuates said mechanism as the consequence of opening movement of the sash, said tip member having an arcuately convex por-

tion that is formed of comparatively soft deformable material and which substantially tangentially contacts the aforementioned plane surface when the arm is being held in set position and while it is being positively moved to the position where it actuates said mechanism as aforesaid, said tip member being turnable to several positions, relatively to the arm, whereat said tip member is frictionally retained to present different areas of its arcuate convex portion to the plane surface with which such tip cooperates.

6. A burglar alarm comprising a unit supportable by a sliding window sash, mechanism comprised by such unit and adapted when actuated to cause the functioning of an alarm, a pivoted actuating arm forming a part of said mechanism, said arm having a set position from which it is movable to a position where it actuates said mechanism, and a tip member, carried by said arm and engageable with a plane surface with respect to which the sash is movable, by virtue of which said arm is held in said set position by said surface and is positively moved to the position where it actuates said mechanism as the consequence of opening movement of the sash, said tip member comprising a plurality of juxtaposed coaxial discs of equal diameters which present axially spaced-apart peripheral ridges that are formed of comparatively soft and somewhat deformable material and which are frictionally held against rotary movement relative to the arm and simultaneously contact the aforementioned plane surface when the arm is being held in set position and while it is being positively moved to the position where it actuates said mechanism as aforesaid, said discs being forcibly rotatable relative to the arm so that different arcuate portions of said peripheral ridges may be presented to said plane surface.

7. A burglar alarm comprising a unit supportable by a sliding window sash, mechanism comprised by such unit and adapted when actuated

to cause the functioning of an alarm, a pivoted actuating arm forming a part of said mechanism, said arm having a set position from which it is movable to a position where it actuates said mechanism, and a tip member, carried by said arm and engageable with a plane surface with respect to which the sash is movable, by virtue of which said arm is held in said set position by said surface and is positively moved to a position where it actuates said mechanism as the consequence of opening movement of the sash, said tip member comprising a disc presenting a periphery that is formed of soft and somewhat deformable material, which is frictionally held against rotary movement relative to the arm and substantially tangentially contacts the aforementioned plane surface when the arm is being held in set position and while it is being positively moved to a position where it actuates said mechanism as aforesaid, said disc being forcibly rotatable relative to the arm so that different arcuate portions of its periphery may be presented to said plane surface.
